UNITED STATES PATENT OFFICE

97,872

DESIGN FOR AN AUTOMOBILE RADIATOR ORNAMENT

Harry Shaw, Royal Oak, and Chris J. Klein, Detroit, Mich., assignors to General Motors Corporation, Detroit, Mich., a corporation of Delaware

Application September 30, 1935, Serial No. 58,769

Term of patent 7 years

To all whom it may concern:

Be it known that we, Harry Shaw and Chris J. Klein, citizens of the United States and residents of Huntington Woods, Royal Oak, county of Oakland, State of Michigan, and Detroit, county of Wayne, State of Michigan, respectively, have invented a new, original, and ornamental Design for an Automobile Radiator Ornament, of which the following is a specification, reference being made to the accompanying drawing, forming a part thereof.

In the drawing:

Figure 1 is a side elevation showing our design, and Figures 2 and 3 are, respectively, a top plan view and a front elevation.

We claim:

The ornamental design for an automobile radiator ornament as shown.

HARRY SHAW.
CHRIS J. KLEIN.
